KARL C. RANDALL, OF EDGEWOOD PARK AND HERMAN K. ANSINGH, OF MURRAYSVILLE, PENNSYLVANIA, ASSIGNORS TO WESTINGHOUSE ELECTRIC & MANUFACTURING COMPANY, A CORPORATION OF PENNSYLVANIA.

FARM CIRCUIT INTERRUPTER.

Application filed June 17, 1920. Serial No. 289,591.

Our invention relates to electrical protective and circuit-interrupting devices and particularly to such devices as are adapted for use with electrical farm equipment.

- 5 ⁵ One object of our invention is to provide a device of the above indicated character that shall be simple and durable in construction, economical to manufacture and effective in operation.
- 10 Another object of our invention is to provide an electrical protective and circuit-interrupting device that shall comprise a substantially minimum number of parts so formed and related as to facilitate the installation operations to a substantially maximum degree and that shall require only ordinary tools and ordinary skill at the place of installation.

15 In electrical farm equipment, it is usual to receive power from a relatively high-voltage line. Switches and all other apparatus connected in circuit with high-voltage lines must, of course, be not only constructed to withstand electrical stresses but also to withstand the effects of use, time and weather.

20 It is essential, particularly in connection with farm equipments where much time and attention would ordinarily be required, that every precaution be taken and every means utilized to simplify and increase the effectiveness of the apparatus.

25 It is our aim to provide a protective and circuit-interrupting device for farm equipments that shall be of the simplest possible construction, which means simplicity of design, few parts and the reduction in number of spare or replacement parts which it will be necessary to have on hand during service conditions.

30 To facilitate the erection of the device, we propose that the various groups of parts, which must necessarily be disassembled for shipping, shall be so designed and arranged as to eliminate any unnecessary adjusting, cutting or drilling on the erection site.

35 It is, also, our aim to have all the parts readily replaceable and, in particular, to have the protective parts, such as fuses and resistors, of very easy access and manipulation.

40 With respect to the latter parts, it is desirable that they be adapted for replacement with the greatest ease and safety because of their usual position of difficult access on a pole or tower and because of the fact that such re-

placements may be frequently performed by the farmers themselves.

45 In practicing our invention, we provide a relatively simple metal-frame supporting structure for disposition at the upper part of a pole or tower. Ordinary pin-type insulators for supporting connections to the line are provided with hooded contact portions projecting laterally therefrom. Tubular insulating members, pivoted at points intermediate their ends, carry yieldable contact members at their upper ends and enclose expulsion fuses in circuit with the contact members and the apparatus to be supplied. A horn-gap lightning arrester and a limiting resistor are supported on the tubular insulator and connected to ground through the supporting structure. A relatively long operating arm extends from the device to a position near the base of the pole or tower and is connected, at its lower end, to an operating handle and a toggle mechanism by which the contact members may be maintained in their closed positions.

50 In the accompanying drawings, Figure 1 is a front elevational view of a protective and circuit-interrupting device embodying our invention.

55 Fig. 2 is a side elevational view of the same with the contact members engaged.

Fig. 3 is a partial side elevational view thereof with the contact members disengaged.

60 Fig. 4 is an enlarged detail view, partially in elevation and partially in section, of the upper portion of the device.

Fig. 5 is an enlarged detail plan view of a portion of the device as illustrated in Fig. 4.

65 Figs. 6, 7 and 8 are detail views of portions of the structure, and

70 Figs. 9, 10 and 11 are views, similar to Figs. 1, 2 and 3 of a modified form of device embodying our invention for connecting a selective plurality of service circuits to the line.

75 A metal-frame structure 1, comprises longitudinal angle members 2, transverse angle members 3 and braces 4, suitably secured, as by a bolt 5, to a pole 6 and has insulators 7 of the ordinary pin type rigidly secured thereto. Caps 8 on the insulators 7 are provided with terminal connectors 9 by which they are connected to high-tension lines (not shown) through conductors 10 and are also provided with laterally extending contact members 11 of substantially inverted channel

shape. A conductor 5^a attached to the upper bolt 5 serves to connect the frame structure 1 to ground.

A transversely-extending shaft 12, supported near its ends in the angle members 2, supports brackets or lever arms 13 which project outwardly therefrom.

As shown more clearly in Fig. 5, the arms 13 are provided with clamping portions 14 which co-operate with clamping members 15 and bolts 16 to secure tubular insulating members 17 intermediate the ends of the latter. The insulating members 17 are provided, at their upper ends, with cap members 18 having portions 19 in which relatively thin yieldable contact members 20 are secured by screws 21, terminal portions 22 projecting into the insulators 17 and clamping portions 23 co-operating with clamping members 24 and bolts 25 to secure one end of each of tubular insulating members 26 projecting outwardly from the ends of the insulators 17.

Complementary clamping members 27 and 28, somewhat similar to the members 23 and 24, are secured to the outer ends of the insulators 26. The clamping members 24 and 28 are similarly provided with portions 29 in which lightning-arrester or horn-gap members 30 are supported by bolts 31. Each clamping member 27 is provided, at its under side, with a portion 32 of substantially inverted cup-shape, for the reception of one end of a limiting resistor 33 which extends to, and rests in, a terminal 34 of substantially cup-shape and disposed at the outer end of an arm 35 extending outwardly and downwardly from the clamping member 15.

The portions 32 and 34 are spaced apart a less distance than the length of the resistor 33 in order that the latter may be securely held in position and, by a simple lifting movement against a spring 36 secured in the portion 32, readily placed in position and released.

A sleeve 37, secured to the lower end of each of the insulating members 17, provides a support for a second line terminal 37^a and a shielding receptacle for a cup member 38 that is attached to the lower end of an expulsion-fuse device 39 having contact members 40 at its upper end for engagement with the portion 22. Slots 41 in the cup member 38 and screws 42 in the sleeve 37, as shown in Fig. 6, constitute a bayonet joint for readily securing and removing the cup member and the fuse 39. A compression spring 43, extending between the inner ends of the screws 42 and the bottom of the cup member 38, serves to bind the fuse device 39 in position and to assist in the release thereof when the cup member 38 is turned in the sleeve 37.

Helical springs 44, each connected at one end to one of the angle members 2 and at its other end to the shaft 12, are adapted to act as cushions for the moving parts, when the interrupter is opened, to prevent fracture of

the refractory members. As shown more clearly in Figs. 7 and 8, bell-crank lever 45 comprises duplicate lever-arm members 46 constructed of insulating material, preferably wood, joined together at one end by bolts 47 and a member 48 that is secured to the shaft 12 by a pin 48a. The lever 45 projects laterally from the shaft 12 intermediate the insulating members 17 and is pivoted, by a pin or bolt 49, to a relatively long operating rod 50 which extends to an operating mechanism 51, disposed adjacent to the lower portion of the pole or tower 6. The operating mechanism 51 comprises a plate 52, secured to the pole or tower 6 by bolts 53, a pin 54 projecting from the plate 52, a handle member 55 pivoted on the pin 54 and to which the arm 50 is pivoted by a pin 56, a sleeve or enlarged portion 57 on the pin 54 for spacing the handle 55 from the plate 52, and stationary locking lugs 58 for co-operation with the bottom portion 59 of the handle member 55 by means of a pin or padlock (not shown) for locking the device in position.

The relation of the pins 54 and 56 of the operating mechanism 51 is such that, when the handle member 55 is turned to its upper position to engage the contact members 11 and 20, the force in the arm 50, caused by the weight of the moving parts, is directed to hold the handle member 55 in its upper position.

When it is desired to operate the circuit interrupter the operator grasps the handle member 55 and turns it in a clockwise direction as viewed in Fig. 2. The movement of the handle member 55 is transmitted through the arm 50 to the bell crank lever 45 and the shaft 12. The turning movement transmitted to the shaft 12 causes the insulating members 17 to turn in a counter-clockwise direction, whereupon the resilient contact members 20 are drawn out of engagement with the laterally extending contact members 11. When it is desired to again close the circuit interrupter, the handle 55 is moved in the opposite direction to turn the resilient contact members 20 in engagement with the stationary contact members 11.

Should an undesired potential, such as is induced by a stroke of lightning or voltage surge, be impressed upon the line conductors 10, arcs are established across the arcing horns 30 which complete circuits from the conductors 10 through the contact members 20, the cap members 18, the arcing horns 30, the resistors 33, the arms 35, the metal frame structure 1 and the conductor 5^a to ground. The circuits just traced are in parallel relation to the circuits through the fuses 39 and the terminals 37^a to the customer's apparatus. As soon as the voltage surge has subsided, the arcs established between the arcing horns 30 are dissipated in a well known manner and the circuits to ground are thereby interrupted.

Should the abnormal conditions exist for an undesirable length of time, the fuses 39 are blown which permanently disconnects the customer's service until the fuses are replaced.

In Figs. 9, 10 and 11, in which similar parts are designated by similar reference numerals, an additional frame structure 60 supports insulators 61 and 62 having contact members 63 and 64, respectively, thereon adapted to be connected in circuit with different service circuits (not shown). The insulators 17 are provided at their lower ends with laterally and downwardly projecting contact members 65 for selective engagement with the contact members 63 and 64.

In this form of device, a stationary contact member 66 of arcuate substantially inverted channel shape is supported on an arm 67 projecting from the upper ends of the insulators 7, and the movable contact member 20 is of loop shape and adapted to have sufficient travel, while still in engagement with the contact member 66, to engage both the contact members 63 and 64, as shown in Figs. 10 and 11.

Further downward movement of the operating rod 50, from the position shown in Fig. 11, will disengage the contact member 65 from the contact member 64 and will, also, disengage the contact member 20 from the contact member 66.

The modification shown in Figs. 9, 10 and 11 provides greater flexibility of control and economy of operation by permitting the selective use of a relatively small lighting-service transformer and a relatively large transformer for operating larger electrical apparatus.

While we have shown and described a particular form of our invention, changes may be effected therein without departing from the spirit and scope thereof, as set forth in the appended claims.

We claim as our invention:—

1. In an electrical protective and circuit-interrupting device, the combination with a supporting structure and a contact member thereon, of a unitary structure pivoted on the supporting structure and comprising a co-operating contact member and a fuse in series circuit relation and a lightning arrester and a resistor in ground circuit relation.

2. In an electrical protective and circuit-interrupting device, the combination with a stationary contact member, of a relatively movable co-operating structure therefor comprising a supporting shaft, a tubular insulating member supported intermediate its ends from said supporting shaft, a contact member above the shaft at one end of the insulating member, a terminal connector at the other end of the insulator and below the shaft, and a fuse connecting the movable contact mem-

ber and the terminal connector disposed in the insulating member.

3. In an electrical protective and circuit-interrupting device, the combination with a stationary contact member, of a relatively movable structure therefor comprising a supporting member, a tubular insulating member supported substantially at its middle on said supporting member, a contact member at one end of the insulating member, a terminal connector at the other end of the same, a fuse connecting the movable contact member and the terminal connector disposed in the insulating member, and hand-operated means permitting the fuse to be readily placed in and taken from the bottom of the insulating member.

4. In an electrical protective and circuit-interrupting device, the combination with a stationary contact member, of a relatively movable structure therefor comprising a grounded supporting member, an insulating member supported on said supporting member, a contact member on the insulating member, a horn-gap member supported on said insulating member and connected to the movable contact member, a second insulating member projecting from the first insulating member and a second horn-gap member supported in spaced relation to said first horn-gap member on said second insulating member and connected to said grounded supporting member.

5. In an electrical protective and circuit-interrupting device, the combination with a stationary contact member, of a relatively movable structure therefor comprising a grounded supporting member, an insulating member supported on said supporting member, a contact member on the insulating member, a horn-gap member supported on said insulating member and connected to the movable contact member, a second insulating member projecting from the first insulating member, a second horn-gap member supported in spaced relation to said first horn-gap member on said second insulating member, and a limiting resistor connected between said second horn-gap member and said grounded supporting member.

6. An electrical protective device comprising a stationary contact member, a grounded movable supporting structure, an insulating member attached to the supporting structure, a contact member and a horn-gap member disposed at one end of the insulating member, a second insulating member disposed at said end of the first insulating member and projecting at substantially right angles therefrom, a second horn-gap member secured to the second insulating member and an impedance member extending between the second horn-gap member and the grounded supporting structure.

7. In a high-potential protective and circuit-interrupting device, the combination with a plurality of protective means and contact members, of a structure for supporting and so moving certain of said contact members as to permit the connection of a main line circuit to a selection of service circuits.

8. A high-potential circuit-interrupting device comprising a stationary contact member of inverted arcuate substantially trough shape, an elongated insulating member pivoted intermediate its ends and carrying a protective device, a contact member at one end of the insulating member for co-operation with the stationary contact member, a second contact member on the insulating member and operatively connected, through the protective member, to the contact member at the other end of the insulator and a plurality of spaced stationary contact members for co-operation with said second contact member.

9. An outdoor circuit-interrupting device comprising a contact member of inverted, arcuate, substantially trough shape, a plurality of contact members constituting portions of different circuits disposed diametrically opposite to points on the arcuate member, a protective device, and a bridging contact structure for selectively connecting the arcuate member, through the protective device, to any of the other contact members.

10. In a high-potential protective and circuit-interrupting device, the combination with a plurality of protective means and contact members constituting portions of different circuit, of a structure for supporting and so moving the protective means and certain of the contact members as to permit the connection of one circuit to any one of a plurality of other circuits.

11. In a high-potential protective and circuit-interrupting device, the combination with a plurality of protective means and contact members, of a structure for supporting and so moving the protective means and certain of the contact members as to permit the connection of one circuit to any one of a plurality of other circuits, through one of the protective means.

12. In a high-potential protective and circuit-interrupting device, the combination with a plurality of protective means having contact members thereon and a pair of spaced co-operating stationary contact members, of a structure for so supporting and moving the protective means and the contact members mounted thereon as to permit the connection of the two stationary contact members in series with one of the protective means.

In testimony whereof, we have hereunto subscribed our names this 4th day of June, 1920.

KARL C. RANDALL.
HERMAN K. ANSINGH.
